COMBINATION INTEGRAL POCKET LINER AND GULLEY BOOT FOR A BILLIARD TABLE OR THE LIKE

Gordon W. Murrey, 14150 S. Figueroa,
Los Angeles, Calif. 90061

Filed Apr. 5, 1973, Ser. No. 348,194

Term of patent 14 years

Int. Cl. D21—01

U.S. Cl. D34—3

FIG. 2

FIG. 3

FIG. 4

FIG. 1 is a perspective view of an integral pocket liner and gulley boot for a billiard table or the like showing my new design;

FIG. 2 is an enlarged scale top plan view thereof;

FIG. 3 is an enlarged scale left side elevational view thereof; and

FIG. 4 is an enlarged scale front elevational view thereof.

I claim:

The ornamental design for a combination integral pocket liner and gulley boot for a billiard table or the like, substantially as shown and described.
